UNITED STATES PATENT OFFICE

MARK H. MARTIN, OF READING, PENNSYLVANIA, ASSIGNOR TO BIRDSBORO STEEL FOUNDRY & MACHINE COMPANY, OF BIRDSBORO, PENNSYLVANIA, A CORPORATION OF PENNSYLVANIA.

LATERAL MOTION DEVICE FOR RAILWAY CAR TRUCKS

Application filed December 12, 1928. Serial No. 325,495.

My invention relates to railway car trucks and has particular relation to devices for permitting lengthwise motion of the bolsters laterally of such trucks.

The general object of my invention is to provide means of novel character for permitting motion of a car truck bolster laterally of the truck wherein chafing surfaces of large area are afforded.

Another object of my invention is to provide a novel construction of means characterized by the provision of roller seat members having column guides provided thereon which guides present large bearing or chafing surfaces.

A further object of my invention is to provide novel lateral motion devices for the bolster of a car truck which include roller seat members having column guides provided with large chafing surfaces, which surfaces are disposed in sliding engagement with the bolster columns for guiding the bolster in vertical directions, the said guides being constructed and arranged to present large bearing or chafing surfaces to the sides of the bolster for guiding the latter and constituting means for stopping it in its movements laterally or transversely of the truck.

Further objects and advantages of the invention will be pointed out in the detailed description thereof which follows or will become apparent as the said description proceeds.

In order that the invention may readily be understood and its advantages from a practical standpoint appreciated, reference should be had to the accompanying drawings in which are illustrated certain embodiments thereof. However, it will be understood that the invention may be embodied in other forms of construction than those shown in the drawings and that various changes may be made in the details of construction without departing from the principle of the said invention.

In the said drawings,—

Fig. 1 is a view partly in elevation and partly in transverse section of the central side portion of a car truck embodying the

novel lateral motion devices invented by me;

Fig. 2 is a view in vertical section taken on the line 2—2 of Fig. 1, one end portion of the bolster being shown in longitudinal section;

Fig. 3 is a view taken on the line 3—3 of Fig. 2 showing the motion device in top plan and the column guides being shown in transverse section;

Fig. 4 is a similar view including the said outer end portion of the truck bolster;

Fig. 5 is a view in horizontal longitudinal section showing a modified construction of device embodying the invention; and

Fig. 6 is a view in transverse section taken on the line 6—6 of Fig. 5.

The lateral motion devices of my invention for the opposite ends of the truck bolster are identical in construction and therefore I have illustrated and shall describe the invention with respect to only one end of the said bolster.

In the drawings, 1 designates a side frame of known construction having spaced bolster columns 2 which form the usual bolster window through which one of the outer ends of the bolster 3 extends. It will be understood that a like window is located at the opposite side of the car truck frame through which the opposite end of the bolster projects. The under side of the outer end portion of the bolster 3 has therein transversely extending recesses or channels 4 which are disposed above similar recesses or channels 5 provided in the top side of the roller seat and spring cap member 6 which rests upon the springs 7. The bottoms of these recesses or channels are curved transversely, as shown in Fig. 2. Rollers 8 are located within the recesses 4 and 5, as shown. The rollers 8 are retained within the recesses or channels 4 and 5 by means of the outside raised portions or ribs 9 and the intermediate raised portions or ribs 10 and the stops 95 or abutments 11 and 12, the said abutments being located in adjoining relation to the opposite ends of the rollers 8. The transversely extending portions 9 and 10 and the longitudinally extending abutments 12 also 100

serve to strengthen the spring cap member 6 between the front and rear edges thereof, as will be obvious.

Formed preferably integrally with the member 6 are vertically extending column guide lugs 12' and intermediate webs 13. The dimensions of these guides are such as to provide unusually large outer bearing or chafing surfaces 14 which are disposed so as 10 to permit sliding engagement of the member 6 with the wear surfaces of the columns 2 of the side frame. These guides extend to the top of the bolster, and as will be obvious, they might be extended to greater heights if 15 desired. The interposition of the said guides between the columns and the sides of the bolster is permitted by providing a bolster the ends of which are sufficiently narrow as compared with the width of the bolster 20 windows to permit the webs 13 of the guides to extend between the sides of the bolster and the columns 2. Consequently the inner sides 15 of the guides may be and preferably are made plane to provide large 25 chafing or bearing surfaces in contacting relation with the adjoining sides of the bolster, the said bolster being guided in its lateral movements thereby. The extent to which the bolster may move laterally of the 30 truck is limited by stop lugs 16 provided thereon adjacent the outer ends of the said bolster, as shown. These lugs 16 engage the outer sides of the outer guide lugs 12' at the opposite sides of the truck upon 35 lengthwise movement of the bolster in one direction or the other laterally of the truck.

In the modified construction shown in Figs. 5 and 6, the column guides 20 provided on the casting 6 are of rectangular shape in 40 cross section and extend between guides or flanges 21 formed on the columns 22. In all other respects the construction shown in these figures is substantially the same as that shown in Figs. 1 to 4, except that the distance 45 between the outer ends of the stop lugs 16 upon the bolster is less than the distance between the upper portions of the bolster columns. One advantage of this construction is that if it should be desired to remove the 50 side frame from the truck to make replacements or repairs, such removal may be effected by removing the springs from the said side frame, which will permit the roller seat casting to be lowered into position to disengage 55 the column guides 20 from the bolster. When this has been done the side frame may be disconnected from the truck and removed without its being necessary to remove or disturb the bolster.

60 It will be seen that I have provided novel lateral motion devices wherein large bearing or chafing areas are formed. Car trucks of known construction may be equipped with the devices invented by me at low cost, and 65 when so equipped, the efficiency and the re-

sistance to wear of the said trucks are greatly increased.

By the words "lateral motion" employed in the specification and claims with respect to the bolster I mean a movement or motion 70 thereof in a direction transversely of the truck.

Having thus described my invention, what I claim and desire to secure by Letters Patent is:

1. In a railway car truck, a roller seat member having rollers thereon, a bolster the outer end of which rests upon the said rollers and is held in spaced relation to the top side of the said member, and column guides integral with said member and embracing the opposite sides of the end portions of said bolster and constituting the sole chafing means therefor. 80

2. In a railway car truck, a roller seat member having rollers thereon, a bolster an outer end of which rests upon said rollers, and column guides integral with said member and being located between the bolster columns and the sides of the said bolster and extending upwardly to a plane approximately coincident with the plane of the top of the adjoining end portion of said bolster. 90

3. In a railway car truck, a roller seat member for supporting one end of a bolster, rollers supported on said member upon which said end of said bolster rests and column guides integrally connected with said member and having inner and outer chafing surfaces of a height approximately equal to the combined thickness of said rollers and said end of said bolster. 95

4. In a railway car truck, a spring cap and roller seat member having guides formed integrally therewith, said guides having outer column chafing surfaces and inner bolster chafing surfaces, said guides extending throughout approximately the entire width of the adjoining portions of said bolster. 105

5. In a railway car truck, a roller seat member having rollers thereon, parallel guides integral with and extending upwardly from the said member, and a bolster an outer end portion of which extends between the said guides and rests upon the said rollers, the tops of said guides being approximately flush with the top surface of the adjoining end portion of said bolster. 110 115

6. In a railway car truck, a roller seat and spring cap member having rollers thereon, column guides formed integrally with the said member, and a bolster one end of which extends between said guides, the said guides having column and bolster chafing surfaces of large area, the tops of said guides and the top edges of the chafing surfaces thereof being located in approximately flush relation to the adjoining end of said bolster. 120 125

7. In a railway car truck, a spring cap and roller seat member having guides formed 130

thereon, said guides having outer column chafing surfaces, inner bolster chafing surfaces, and the said guides constituting stops with which engage the stop lugs of the bolster of the said truck upon lengthwise movement of the said bolster laterally of the said truck.

5 8. In a railway car truck, a spring cap and roller seat member, a bolster the outer end of which is carried by the said member, the said bolster having stop lugs formed thereon, and guides formed integrally with the said member, the said guides comprising chafing surfaces which engage the columns of the side frame of the said truck, chafing surfaces which are engaged by the said bolster, and the said guides constituting stops with which engage the stop lugs of the said bolster upon lengthwise movement of the latter laterally of the said truck.

10 9. In a railway car truck, a side frame having a bolster opening therein, springs located in said opening, a roller seat and spring cap member supported by said springs, said member having column guides formed thereon, 25 rollers resting on said member, and a bolster one end of which extends through said opening and is supported upon said rollers, said bolster having outwardly projecting stop lugs formed on said end, the distance between the outer ends of said stop lugs being less than the width of the upper portion of the said bolster opening.

15 10. In a railway car truck, a side frame having a bolster opening therein, springs located in said opening, a spring cap member mounted upon and supported by said springs said member having column guides formed thereon and projecting upwardly therefrom, and a bolster one end of which projects through the said opening and is supported by the said springs, said bolster having outwardly projecting stop lugs formed upon the opposite sides of said end, the distance between the outer ends of said stop lugs being less than the distance between the opposite sides of the upper portion of said opening.

20 In testimony that I claim the foregoing as my invention I have hereunto signed my 50 name this 10th day of December, A. D. 1928.

MARK H. MARTIN.
